(57) **CLAIM**

The ornamental design for a shutter assembly, as shown and described.

DESCRIPTION

FIG. 1 is a perspective view of the shutter assembly according to the present design;

FIG. 2 is a front view of the slat of the shutter assembly illustrated in FIG. 1 showing the slats of the shutter assembly according to the present design;

FIG. 3 is a rear view of the slats of the shutter assembly illustrated in FIG. 1 showing the slats of the shutter assembly according to the present design;

FIG. 4 is a first side view of the slats of the shutter assembly illustrated in FIG. 1 showing a right side of the slats of the shutter assembly according to the present design;

FIG. 5 is a second and opposite side view of the slats of the shutter assembly illustrated in FIG. 1 showing a left side of the slats of the shutter assembly according to the present design;

FIG. 6 is a top view of the slats of the shutter assembly illustrated in FIG. 1 showing the slats of the shutter assembly according to the present design;

FIG. 7 is a bottom view of the slats of the shutter assembly illustrated in FIG. 1 showing the slats of the shutter assembly according to the present design; and

FIG. 8 is a front view of the rails of the shutter assembly illustrated in FIG. 1 showing the rails of the shutter assembly according to the present design;

FIG. 9 is a rear view of the rails of the shutter assembly illustrated in FIG. 1 showing the rails of the shutter assembly according to the present design;

FIG. 10 is a top view of the rails of the shutter assembly illustrated in FIG. 1 showing the rails of the shutter assembly according to the present design;

FIG. 11 is a bottom view of the rails of the shutter assembly illustrated in FIG. 1 showing the rails of the shutter assembly according to the present design;

FIG. 12 is a first side view of the rails of the shutter assembly illustrated in FIG. 1 showing a right side of the rails of the shutter assembly according to the present design; and,

FIG. 13 is a second and opposite side view of the rails of the shutter assembly illustrated in FIG. 1 showing a left side of the rails of the shutter assembly according to the present design. The claimed design comprises the elements shown in solid lines. The broken lines in the drawings represent either portions of the shutter assembly that form no part of the claimed design, or environmental subject matter that forms no part of the claimed design. Additionally, the shutter assembly is shown with symbolic breaks in width and length. The appearance of any portion of the article between the break lines forms no part of the claimed design. The broken lines form no part of the claimed design.

1 Claim, 8 Drawing Sheets
